UNITED STATES PATENT OFFICE.

JUDSON A. DE CEW, OF MONTREAL, QUEBEC, CANADA.

OIL AND SOAP SOLUTION.

1,337,546.

Specification of Letters Patent. Patented Apr. 20, 1920.

No Drawing.

Application filed May 17, 1918. Serial No. 235,137.

To all whom it may concern:

Be it known that I, JUDSON A. DE CEW, a subject of the King of Great Britain, and resident of the city of Montreal, in the 5 Province of Quebec and Dominion of Canada, have invented certain new and useful Improvements in Oil and Soap Solutions, of which the following is a full, clear, and exact description.

10 This invention relates to a composition which can be used as a sizing material for paper stock and which can also be employed in the flotation of paper and pulp fibers in recovery systems. It may also be used for 15 the purpose of introducing coagulant into the solutions of industrial wash waters for the purpose of altering the surface tension and producing a tendency to form a permanent froth with air, and by means of this 20 froth any suspended matter is recovered by flotation.

The principal object of my invention is to provide a product which can be forced into the waste waters containing pulp or 25 paper fibers, preferably with more or less agitation, which product will produce a frothing condition in the waste waters, permitting gas bubbles to rise and adhere to the fibers, floating them to the surface. My 30 product has, however, the further quality of acting as a very satisfactory sizing material, so that when the recovered fibers are carried back to the paper, beneficial sizing results will be produced.

35 According to my invention, I first dissolve any oil in a concentrated solution of any soap, incorporating say about one hundred pounds of oil in approximately the same amount of soap, but this proportion 40 may be adjusted to meet various requirements. The next step in the process is to dilute this soap solution in such a manner as to prevent separation of the oily material in the form of globules and this is 45 best accomplished by an emulsifying process, such as that described in Reissue Patent No. 12,549 or in my application, Serial Number 195,607. It is possible to obtain a soap solution with a concentration 50 of approximately 2% total solids, which holds in colloidal solution or permanent emulsion the oil originally incorporated. The soap which is used for dissolving the oil may be soap made from any saponifiable 55 material. When solutions such as above described are incorporated into the paper stock

in the mixer, all the material incorporated therewith is precipitated on to the paper stock, when the soap solution is coagulated in the usual manner, by means of aluminum sulfate or other precipitant. It is thus incorporated into the pulp of the paper mass and according to this treatment small quantities of oil in proportion to the weight of the paper may be incorporated. The paper 60 made from this pulp has the property of being waterproof without the disadvantage of an excess of oil. Furthermore, paper made from pulp recovered in this manner still retains its strength, pliability and 70 moisture, whereas an oil impregnated paper has less strength and is disagreeable to use.

When this product is used in connection with the flotation process as described in my U. S. patent application, Serial Number 75 217,691, a very small quantity of the oily product is introduced preferably under agitation with air into the waste waters to produce a more or less permanent frothing condition. This emulsion product has a 80 coagulating action upon the pulp fibers which increases the tendency of the fibers to draw together in a mass, thus permitting them to be more easily separated and floated to the surface. This product not only has the de- 85 sired effect in facilitating the formation of gas bubbles and making them adhere to the surface of the floating fibers, but also produces beneficial sizing results when the recovered material is returned to the paper 90 machines.

If this product is used in the recovery of other organic wastes such as are lost from starch factories, breweries, etc., then an edible oil may be used which would not 95 alter the food value of the recovered material.

Having thus described my invention, what I claim is;—

1. A stable product for the purpose specified, consisting of a dilute solution of oil held in colloidal solution by means of a highly dilute soap.

2. A stable product for the purpose specified, consisting of a highly dilute aqueous 105 colloidal solution of oil produced by diluting in water without decomposition a perfect blend of soap and oil.

In witness whereof I have hereunto set my hand.

JUDSON A. DE CEW.
